UNITED STATES PATENT OFFICE.

JOHN L. LAUGHLIN, OF LOUISVILLE, KENTUCKY, ASSIGNOR TO B. F. AVERY
& SONS, OF SAME PLACE.

DOUBLE PLOW.

SPECIFICATION forming part of Letters Patent No. 297,815, dated April 29, 1884.

Application filed February 14, 1884. (No model.)

To all whom it may concern:

Be it known that I, JOHN L. LAUGHLIN, of Louisville, in the county of Jefferson and State of Kentucky, have invented a new and useful 5 Double Sugar-Land Plow; and I do hereby declare that the following is a full, clear, and exact description thereof, reference being had to the accompanying drawings, making part of this application.

10 My invention relates to certain new and useful improvements in what I denominate a "double sugar-land plow," and as to most of its features is more especially adapted to this species of implement, though, as to some points 15 therein, my invention may be applied to plows designed for usessomewhat different from those for which the implement herein described and shown has been gotten up.

20 My invention consists in the novel devices and combinations of devices which will be found hereinafter more fully described, and which will be most particularly pointed out in the claims of this specification.

25 To enable those skilled in the art to which my invention relates to understand and practice the same, I will now proceed to more fully explain the several novel features of my improved implement, referring by letters to the accompanying drawings, forming part of this 30 specification, and in which I have illustrated my invention as carried out in that form which is the best now known to me, and in which I have so far practiced it.

35 In the drawings, Figure 1 is a side view or elevation of one of my improved implements called a "double sugar-land plow." Fig. 2 is a top view of the same. Fig. 3 is a bottom view of the same. Fig. 4 is a vertical cross-section of the same at the line xx of Fig. 1, 40 drawn on a somewhat larger scale. Fig. 5 is a vertical cross-section at the line yy of Fig. 1, same scale as Fig. 4. Fig. 6 is a partial cross-section or detail view, same scale, showing merely the arrangement of the beam, standard, &c. Fig. 7 is a detail or skeleton view, same scale as Fig. 1, showing the beam-standard in side view; and Fig. 8 is a detail view of the draft-rod detached.

In the several figures the same part will be

found designated by the same letter of reference.

The beam of the plow is duplex—that is, it is composed, as shown, of two bars or beams, C C, which are arranged side by side about parallel with each other, and a short distance 55 apart during the greater part of their length, but spring close together at their forward ends, where they are held in union by a suitably-formed metallic cap-piece, c , secured to them.

60 The metallic standard a , which is preferably of the curved form shown, firmly supports the shares (or double point) D and the mold-boards B B, is formed or provided with a head or cap, a^2 , and, being rather narrow (or plate-like) in cross-section, fits and is confined in between the two parts of the duplex beam, where it is securely held by bolts or otherwise, as shown at e , Fig. 7.

65 A A are the usual handles of the plow, secured thereto as shown. E is the gage-wheel, 70 (for regulating the depth of cut,) and e the carrying-wheel, by means of which the weight of the plow is carried over the ground with a rolling instead of a sliding frictional movement. The frog h is by preference welded each 75 part to the landsides G G, between which lies the standard, these parts being securely bolted together, as shown, and the landsides G being extended rearwardly and carrying the lower end of the frame i , in which is hung 80 the vertically-adjustable axle of the carrying-wheel e , before alluded to.

75 b is the colter, (which is of the circular disk-like type,) the hub of which is supported properly by angle-irons or metallic frames d d , depending from either side of the plow-beam and secured thereto, as shown. (See Figs. 1 and 5.)

85 H is a device which I term the "rudder." It is arranged in rear of the lower portion of the plow-beam, and projects centrally downward to a point some distance below the level of the base of the plow, and has its lowermost part made knife-edged or chisel-like by preference. It may be made vertically adjustable, if deemed expedient, and its function is 95 to enter the earth some distance below the line of deepest penetration of the plow-point,

for the purpose of steering or guiding the plow, in a manner to be presently explained.

The gage-wheel E is, as usual, made vertically adjustable, for the well-known purpose 5 of gaging the depth of cut of the plow.

As will, of course, have been seen, so far the plow proper, with its single point D flaring from a point centrally beneath the beam in each direction, and with its duplicate mold- 10 boards B B, is what is termed "double-nosed," and hence adapted to turn a furrow to each side and cut trenches, and is more especially designed for this sort of work.

K is the draft-rod, which is composed (see 15 Fig. 8) of a rearmost double or link-like portion and a forward single or rod-like section, the two coupled together at l, and the back end of the link-like portion attached to a staple or eye, m, which projects from the under 20 side of the beam a short distance in rear of the standard a. The forward end of this duplex draft-rod K carries a ring, n, to which the draft-power may be applied, and the double or link-like construction of its back half 25 or portion permits it to straddle or yoke around both the plow-standard a and the disk-like colter b, all as clearly indicated in the drawings.

As will be readily understood, the implement herein described and shown is designed 30 for use mainly in the cultivation of sugar-cane, being specially adapted to splitting and opening the ridges in which the cane is planted.

In the use of the implement shown, the 35 gage-wheel E having been set or adjusted properly, and the carrying-wheel e having been adjusted to the right position, the double-nosed point D and mold-boards B B will penetrate the earth and turn over a double furrow, 40 forming perfectly the trench in or splitting the ridges usually made for planting the sugar-cane. In doing such work such a nosed plow is apt to cut to one side of and run out of the ridge the crown of which is being split open 45 or trenched, on account of the unevenness of the resistance offered to the opposite edges of the double share, and the uneven resistance to the two mold-boards that is likely to occur; and especially is this liable to happen if the 50 draft of the team be not kept in perfect line with the central line of the ridge. To overcome successfully this difficulty in the practical working of all implements of the kind shown, I have combined with the plow the 55 rudder H, which offers little or no resistance to the forward movement or progress of the plow, but presents to the resistance of the earth, sidewise of the implement, its broad and deeply-inserted sides in such manner as 60 to check any inclination of the plow to run out of the ridge at either side of the latter. Thus this rudder-like device, while not materially increasing the draft of the plow, operates successfully to keep the plow in place laterally, 65 or in the proper working line of travel against any tendency of an uneven pressure on the op-

posite working faces of the share and mold-boards to turn the plow out of its proper course. Of course this feature of my improved implement may be used with advantage on any 70 double-nosed plow, and may be employed in a plow which may not have in it the other features or points of my invention.

It will be seen that by forming the plow-beam of two bars or pieces, (or by making it 75 duplex,) as shown and described, not only am I enabled to produce a light, strong, and in other respects desirable beam, but I also gain these great desiderata, viz: I can successfully use a colter of much greater size or diameter 80 than is possible where a solid beam (through which the colter cannot penetrate) is used, and I can securely combine, in a most economical and desirable manner, the standard and beam, the former ascending between the parts of the 85 latter, between which it is securely clamped and held, the head a² giving a horizontal bearing on the tops of the two pieces C C of the beam, while cross-bolts some distance below this bearing-point operate in conjunction therewith to produce a secure attachment of the standard to the beam. I consider this feature of the duplex or double beam as of great importance in my improved implement, and this point or part of my invention, it will be seen, 90 can be used with great advantage in other types of plows than that shown, as well as in other double-nosed plows not embracing the other features of my invention.

The opportunity afforded by the duplex or 100 centrally-open beam for an increased size of colter will be readily perceived by a glance at Figs. 1 and 5, from which it will be seen that the colter b can extend clear up above the level of the top of the plow-beam; and it will of 105 course be understood that all the mechanical qualities and effects of the duplex beam might be gained by the use of a single beam or bar simply cut through or slotted out vertically at the proper localities for the accommodation of 110 the standard and colter, in the manner described; but I deem the formation of the beam of two pieces with the intervening space, as shown, the better form in which to carry out 115 this feature of my invention.

It will be seen that by making the frog in 120 two pieces, h h, welded to the landsides G G, as explained, and then bolting on the standard (and also the rudder H) intermediate of the landsides, as shown, a very simple, strong, light, and durable construction results, in which the plowshare and mold-boards are easily and securely held in place, and in which compactness, strength, and economy of manufacture are combined. The extension backward of the landsides G, and their combination, as shown, with the pendent bars i i, in which are adjustably journaled the opposite ends of the axle of the carrying-wheel e, enable me, it will be seen, to make this portion 130 of the implement light, strong, and simple.

Of course many variations may be made in

the mere details of the construction of the implement shown without either changing essentially its general character or materially varying it as to any one of its novel features; and 5 the sizes, proportions, and precise relationships of the parts may of course be varied more or less without departing from the spirit of my invention.

What I claim herein as new, and desire to 10 secure by Letters Patent, is—

1. In combination with a double or duplex beam, a revolving colter arranged to rotate partially within the slot or space afforded for its accommodation between the two parts of 15 said duplex beam, all substantially in the manner and for the purpose set forth.
2. In combination with the beam and standard of a double-nosed plow, the landsides G G, extending rearwardly from the lower portion 20 of the standard, the vertical bars *i i*, secured at their lower portions to the landsides and at their upper ends to the beam, and a carrying-

wheel *e*, the whole constructed and operating substantially as described, for the purposes set forth.

3. In combination with the double or duplex frog *h h* and the two landsides G G, to which the parts of said frog are secured, an intermediate-arranged standard, *a*, the whole constructed, arranged, and operating in substantially the manner and for the purposes set forth.

4. The combination, with the double plow, a duplex or a slotted beam, and a colter revolving partially within said beam, of the landsides G G, having frogs *h h*, the bars *i i*, a carrying-wheel, *e*, and the fixed rudder-plate H, all substantially as shown and described.

In testimony whereof I have hereunto set my hand this 4th day of February, 1884.

JOHN L. LAUGHLIN.
